UNITED STATES PATENT OFFICE.

CHARLES E. CONNER, OF AUBURN, MAINE, ASSIGNOR TO UNITED SHOE MACHINERY CORPORATION, OF PATERSON, NEW JERSEY, A CORPORATION OF NEW JERSEY.

ASSEMBLING-MACHINE.

1,382,762.

Specification of Letters Patent. Patented June 28, 1921.

Application filed September 10, 1918. Serial No. 253,411.

To all whom it may concern:

Be it known that I, CHARLES E. CONNER, a citizen of the United States, residing at Auburn, in the county of Androscoggin and 5 State of Maine, have invented certain Improvements in Assembling-Machines, of which the following description, in connection with the accompanying drawings, is a specification, like reference characters on the 10 drawings indicating like parts in the several figures.

The present invention relates to improvements in machines for assembling shoe parts and is herein set forth with particular reference to its utility in assembling and securing counters such as previously molded counters in the manufacture of turn shoes made according to the method disclosed in Patent No. 1,302,994, granted upon an application filed in the name of J. K. Thissell, 20 although the invention is not limited to such use.

According to this method of incorporating a counter in a turn shoe a previously molded counter is attached to the heel portion of the 25 sole after the shoe upper has been secured to the sole inside out in the well-known manner of making turn shoes but prior to turning the shoe right side out. It is of especial 30 importance in practising this method properly to locate the counter in an upright or final position relatively to the sole with particular reference to the interior dimensions of the shoe after the shoe is turned 35 to obtain a shoe of the desired predetermined size and to insure the second last fitting of the shoe snugly. Moreover, it is essential 40 that the counter should be permanently and strongly attached in the position it is finally to occupy in the finished shoe in spite 45 of any handling which would be liable to displace the counter. A further difficulty arises from the heel seat nailing operation which has heretofore been performed after 50 the shoe is turned since the heel seat nails unless carefully inserted are liable to interfere with subsequent heel attaching and finishing operations on the shoe and also the heel seat nailing operation necessitates an additional handling of the shoe.

The invention has for its objects to provide for accurately, efficiently and economically assembling molded counters and turn shoe parts and to insure that the counters 55 will be so incorporated in the shoe that they

will be permanently in the correct relation to the other parts and especially in correct lengthwise relation to the shoe.

With the above and other objects in view the illustrated machine, which constitutes a preferred embodiment of the invention, comprises a novel organization of means for supporting the various shoe parts including the shoe upper, means for supporting the counter, and means for effecting a relative movement of the said shoe and the said counter to present the counter in predetermined assembled relation to the shoe upper. As herein described, the turn shoe sole is attached inside out to the shoe upper and is supported on a last in inverted position and the means for holding the flanged counter are constructed and arranged to enter the counter and support it in an upright position relatively to the heel seat portion of the sole to which the counter is to be attached. In the operation of the machine illustrated, the shoe support carrying the shoe and the counter support carrying the counter are moved relatively into a position to seat the counter in its final position on the heel seat of the sole and then fastenings are inserted by the machine permanently to attach the counter in the said position to the sole of the shoe.

In the illustrated machine relatively adjustable counter and sole edge gages are provided respectively for holding the counter and for positioning the rear of the sole in proper relation to the counter according to the particular style and size of shoe being made.

As herein illustrated and in accordance with a further feature of the invention, the fastening inserting mechanism is preferably constructed and arranged to insert a plurality of fasteners in a single operation to secure the flange of the molded counter to the underlying heel seat portion of the sole. By attaching the counter to the sole in a single operation not only is the counter more strongly attached in its final position in the shoe, but there is less liability of the counter being displaced as through carelessness in subsequent handlings of the shoe.

Other objects and features of the invention will appear from the following description when considered in connection with the accompanying drawings which illustrate a preferred embodiment of the invention and

the invention will then be pointed out in the appended claims.

In the drawings,

Figure 1 is a view in side elevation of a fastening inserting machine in the construction of which a preferred form of my improvements has been embodied, parts of the construction being shown in section and other parts being broken away for clearness 10 of illustration;

Fig. 2 is a view in side elevation and partly in section illustrating the relative location of the shoe and the operating elements of the machine prior to the insertion of the 15 fastenings to attach the counter to the shoe;

Fig. 3 is a part elevation of the counter supporting means and nail block of the machine;

Fig. 4 is a perspective view of the counter 20 supporting means and nail block;

Fig. 5 is an enlarged perspective of the shoe and counter locating means;

Fig. 6 is a perspective view of a shoe after 25 being operated upon by this machine.

In the accompanying drawings the invention is illustrated as embodied in a heel attaching machine of the type shown in United States Patent No. 446,885, granted Feb. 24, 1891, on an application of Joseph H. Pope 30 to which reference may be had for a more complete description of the machine construction not herein disclosed in detail.

The present invention, however, is not limited in its application to that or any 35 other particular type of machine.

The machine comprises a frame 2 provided with a stationary cross bar 4 in which are formed a plurality of driver passages 6 through which reciprocate the drivers 8 40 carried by the cross head 10. The cross head is secured to the upper ends of side rods 12 which reciprocate in vertical journals 14 formed in the frame 2. The reciprocation of the cross head 10 may be effected in any suitable manner, for example, through a lower cross head connected with an eccentric on the driving shaft of the machine as shown in the patent to Pope above referred to. In the lower part of the frame 50 2 vertical guideways are provided for a jack carriage support and a superimposed jack carriage 16. The latter is provided with horizontal ways 17 for the jack 18 which carries the shoe to be operated upon, the 55 jack comprising a vertically adjustable heel post 19 carrying a last pin 20 and an adjustable toe post 21 to support the toe of the shoe. The jack carriage 16 is elevated to bring the heel seat portion of the shoe in 60 work clamping relation to the nail inserting mechanism by suitable power operated mechanism in the base of the machine. As shown in the patent to Pope above referred to, a nail loader 22 is provided to furnish 65 the nail block with the required number of

nails to be driven, these nails being preferably of the headed type to insure the holding effect of the nails.

Centrally mounted on the under surface of the stationary cross bar 4 by means of the bolt 24 and dowel pins 26 is a block 28 which serves to support a shoe counter 30 for attachment in upright position on the heel seat of the shoe 32. This block 28 is shaped to enter the smallest size of counter 75

to be used so that it will not be found necessary to substitute various sizes of counter supporting blocks when operating upon different sizes of shoes and it has its bottom surface slightly concaved to correspond to 80 the convexed heel seat surface of the shoe, thus insuring a proper seating and clamping of the inturned flange of the counter on the heel seat. Driver guiding passages 6 are

also formed in this counter block in continuation of the driver passages 6 in the cross bar 4. On opposite sides of the counter block 28 and near its forward edges are a pair of spring clips 36 extending downwardly and rearwardly to a point near the 85 lower edge of the block for retaining the counters on the block. These clips, which are conveniently narrow strips of spring steel, depend from ears 38 carried by a left and right threaded screw 40 extending transversely through the block and they have their outer ends curved slightly inwardly as

shown in Fig. 3 so as to grip the counter and cause it better to hug the counter block. The screw 40 which has heads 42 at either 90

end provides for simultaneous lateral adjustment of the clips 36 to accommodate different sizes of counters on the block, a set screw 44 being provided to lock the screw in any of its adjusted positions. Extending 95

downwardly from the under side of the cross bar 4 to which it is secured by the screw 48 and against the rear surface of the block 28 is another spring clip 50 which co-operates with the clips 36 correctly to position 100

the counter on the counter supporting block and hold it against displacement. The driver guiding passages 6 in the cross bar 4 and in the counter block 28 are located as 105

near as practical to the outer wall of the block 110 28 in a U-shaped design to insure the nails being driven through the inturned flange of the counter and adjacent to its inner wall. Also, the drivers 8 and driver passages 6 are

so arranged that they do not insert fastenings forwardly of substantially the heel breast line of the shoe to be operated upon; otherwise, in turn shoes, the clenched ends 115 of the nails would appear on the finished surface of the sole.

The shoe and the counter are accurately positioned relatively to each other by means of a shoe engaging gage 52 and a counter engaging gage 54 both of which are mounted 120

for vertical adjustment and for a lim- 125

The shoe and the counter are accurately positioned relatively to each other by means of a shoe engaging gage 52 and a counter engaging gage 54 both of which are mounted 130

ited yielding movement so that they will accompany the shoe in its slight downward displacement when subject to pressure. For this purpose a rod 56, the upper end of which carries the gages 52, 54, is slidingly mounted at its lower end in a bracket 58 and is normally maintained in an elevated position by a compression spring 60 which encircles the end of the rod as shown in Fig. 1. Near its upper end the rod 56 slides in an angle piece 62 having a threaded shank 63 which extends through the forks of a bracket 64 on the machine frame. An adjusting nut 65 on the shank 63 serves to determine the adjusted position of the shoe or sole gage and, therefore, the position of the shoe longitudinally of the counter. This gage is of considerable importance in the use of the machine and in the performance of the steps attendant upon the attachment of the counter to the shoe, since the location of the shoe relatively to the counter when attached predetermines the interior dimensions or final size of the shoe, and unless such accuracy in relatively locating the shoe and counter is insured subsequent operations on the shoe are impaired and a shoe of the wrong size is produced. The counter gage 54 is located immediately above the sole gage 52 and is mounted for adjustment relatively to the sole gage and in the direction but independently of the sole gage adjustment by means of a set nut 66 on the end of the rod 56, which projects through a slot in the counter gage. The forward end or counter engaging surface 67 of the gage 54 is inclined backwardly as shown in Fig. 2 so as to force the vertical inner wall of the counter, particularly at its junction with the inturned flange portion, against the lower edge of the counter supporting block.

In the use of the invention with the machine herein illustrated, the shoe upper is first attached to the sole while inside out as described in the above mentioned patent to Thissell. The jack 18 is next pulled outwardly in the ways 17 of the jack carriage and the shoe 32 on the last is placed on the heel post 19 with its toe resting on the toe post 21, the jack being then adjusted for height and for the length of the shoe in question. The jack and the shoe are then pushed rearwardly into the machine until the rear end of the sole of the shoe engages the sole gage 52 which is then adjusted by means of the adjusting screw 65 to locate the heel seat of the shoe in predetermined longitudinal relation to the counter 30.

In the next step of the process the previously molded counter of the proper size and shape to fit the shoe which is being made is placed over the counter supporting block 28, the side walls of the counter being sprung under the side clips 36 which, by reason of their inwardly curved lower ends

engage the counter near its lower edge and hold it in position on the block. When counters are being used which are not held in some way in final position against spreading; for example, a half molded counter, the side clips also serve to maintain the counter in the desired shape on the block, the spread of the counter being predetermined by the lateral adjustment of the clips through the adjusting screws 40. The rear upper edge of the counter is also definitely located on the block by the clip 50 and to insure the firm seating of the counter with its inturned flange overlying the bottom of the block and its inner wall in contact with the wall of the block the inclined surface 67 of the counter gage 54 is forced against the lower edge of the counter as shown in Fig. 2. Thus the counter is firmly supported in predetermined position relatively to the shoe and the inturned flange of the counter is in position on the bottom of the block to receive the nails inserted through the driver passages 6. It will be obvious to those skilled in the art that with the Thissell practice of incorporating molded counters in turn shoes the accurate location of the counter upon the heel seat of the sole is of especial importance since it determines the interior dimensions of the shoe after it is turned right side out and therefore the final size of the shoe. By providing mechanical means for supporting the counter of the shoe in a predetermined position and for supporting the shoe in assembled relation to the counter, including provision for effecting a fine adjustment of the shoe in the direction of its length, as in the illustrated machine, the two shoe parts may be permanently associated with absolute accuracy and uniformity.

After the shoe and the counter have been properly positioned the machine is started and the jack 18 is elevated in direct vertical alinement with the counter supporting block 28 whereupon the counter is seated upon the heel seat of the shoe with increased and positive pressure. During this relative movement of the shoe and the counter the gages 50 and 52 are carried with them, thus preventing their displacement and then as the shoe and counter settle under the pressure, the gages yield. While the shoe is thus held under pressure the attaching nails which are preferably headed are deposited by the loader 22 in the driver passages 6 and driven by the drivers 8. As previously explained the driver passages are located near the outer wall of the counter supporting block and consequently they pass through the inturned flange of the counter and the margin of the sole of the shoe being clenched upon the usual iron bottom provided on the last. The jack is then lowered which removes the counter from its support

and pulled forward so that the shoe may be removed.

The method which has been disclosed above is not claimed herein but in application Serial No. 343,365, which is a division of this application.

Having illustrated and described my invention, what I claim as new and desire to secure by Letters Patent of the United States is:

1. In a machine of the class described, the combination of means for supporting shoe parts, including a shoe upper, means for supporting a counter, and mechanism for effecting a relative movement of the said two means to present the counter in predetermined assembled relation to the shoe upper.

2. In a machine of the class described, the combination of means for supporting shoe parts including a shoe upper, means for supporting a counter, mechanism for effecting a relative movement of the said two means to present the counter in predetermined assembled relation to the shoe upper, and means for securing the counter and the upper together in assembled relation.

3. In a machine of the class described, the combination of means for supporting a turn shoe sole and an attached upper, means for supporting a flanged counter, and mechanism for effecting a relative movement of said two means to present the counter with its flange in position to be permanently secured to the heel seat portion of the shoe.

4. In a machine of the class described, the combination of means for entering a shoe and supporting the heel end of the shoe sole, an opposing member shaped to enter and support a counter, and mechanism for effecting relative approaching movement of said means and member to locate the counter in predetermined relation to the sole.

5. In a machine of the class described, the combination of means for supporting a lasted shoe, means for supporting a flanged counter in register with the heel seat of the shoe and facing away therefrom, and means for effecting relative approaching movement of the two supporting means to press the flange of the counter upon the heel seat of the shoe.

6. In a machine of the class described, the combination of means for entering a shoe and supporting the heel end of the shoe sole, an opposing member shaped to enter and support a flanged counter, mechanism for effecting relative approaching movement of said means and member to locate the counter in predetermined assembled relation upon the sole, and means for securing the counter in said relation to the sole of the shoe.

7. In a machine of the class described, the combination of means for supporting a turn

shoe sole and an attached upper, means for supporting a flanged counter, mechanism for effecting a relative movement of said two means to present the counter with its flange in position to be permanently secured to the heel seat portion of the shoe, and mechanism for inserting fastenings to fasten the counter by its flange to the sole of the shoe.

8. In a machine of the class described, the combination of means for supporting a lasted shoe, means for supporting a flanged counter in register with the heel seat of the shoe and facing away therefrom, and means for securing the flange of the counter to the shoe.

9. In a machine of the class described, the combination of means for supporting a lasted turn shoe prior to turning, a member shaped to enter and support a flanged counter in register with the heel seat of the shoe and facing away from the shoe, mechanism for effecting relative approaching movement of said means and member to press the flange of the counter upon the heel seat of the shoe, and means for fastening said flange to the shoe.

10. In a machine of the class described, the combination of means for supporting a lasted turn shoe prior to turning, a member shaped to enter and support a flanged counter in register with the heel seat of the shoe and spaced therefrom, mechanism for effecting relative approaching movement of said means and member to press the flange of the counter upon the heel seat of the shoe, and means for fastening said flange to the shoe.

11. In a machine of the class described, the combination of means for supporting a lasted shoe, means for supporting a flanged counter in register with the heel seat of the shoe and facing away therefrom, and means for inserting at a single operation, a plurality of fastenings to secure the flange of the counter to the shoe.

12. In a machine of the class described, the combination of means for entering a shoe and supporting the heel end of the shoe sole, an opposing member shaped to enter and support a flanged counter, mechanism for effecting relative approaching movement of said means and member to press the flange of the counter upon the sole, and mechanism for inserting a gang of fastenings to secure the counter by its flange to the sole of the shoe.

13. In a machine of the class described, the combination of means for supporting shoe parts including the shoe upper, means for supporting a counter, mechanism for effecting a relative movement of said two means to present the counter in predetermined assembled relation to the shoe upper, and mechanism for inserting at a single op-

eration a plurality of fastenings to secure the counter and the upper together in assembled relation.

14. In a machine of the class described, 5 the combination of means for supporting a lasted and sewed turn shoe, means for supporting a counter, devices to position the shoe and the counter relatively in the direction of the length of the shoe, mechanism for 10 effecting a relative movement of the two supporting means to present the counter in predetermined assembled relation on the heel seat of the shoe, and mechanism for inserting fastenings for permanently attaching 15 the counter to the shoe.

15. In a machine of the class described, the combination of means for supporting the heel end of a shoe sole, an opposing means shaped to support a counter and to press the 20 flange of the counter upon the sole, and mechanism operating through one of the said means constructed and arranged to insert a plurality of fastenings simultaneously to attach the counter to the sole.

25 16. In a machine of the class described, the combination of means for entering a shoe and supporting the heel end of the shoe sole, an opposing member shaped to enter and support a flanged counter, mechanism 30 for effecting relative approaching movement of said means and member to press the flange of the counter upon the sole, and mechanism operating through the counter supporting member for inserting fastenings 35 to secure the flange of the counter to the sole of the shoe.

17. In a machine of the class described, the combination of means for supporting a lasted and sewed turn shoe, devices for supporting 40 a counter including means to hold the counter in a predetermined shape, and means for effecting relative movement between the counter and the shoe to locate the counter in predetermined position upon the 45 sole.

18. In a machine of the class described, the combination of means for supporting a lasted and sewed turn shoe, devices for supporting a counter including means to hold 50 the counter in a predetermined shape, mechanism for effecting relative movement between the counter and the shoe including means to locate the counter in predetermined position upon the sole, and mechanism 55 for inserting fastenings to attach the counter by its flange to the sole in the position in which it is held by the counter supporting devices.

19. In a machine of the class described, 60 the combination of an upright shoe supporting jack, a nailing die above the jack, an approximately counter-shaped member depending from the nailing die, mechanism for effecting relative approaching movement 65 of the jack and said member, and means for

driving a gang of nails downwardly through said member into a shoe upon the jack.

20. In a machine of the class described, the combination of an upright shoe supporting jack, a depending approximately 70 counter-shaped member above the jack, means for retaining a counter upon said member, means for effecting relative approaching movement of the jack and said member, and means for securing the counter 75 to the shoe.

21. In a machine of the class described, the combination of a shoe supporting jack, a projecting, approximately counter-shaped member in alinement with the heel seat of a 80 shoe upon the jack, means for effecting relative approaching movement of the jack and said member to position the counter upon the heel seat of the shoe, and means for securing the counter to the shoe. 85

22. In a machine of the class described, the combination of a shoe supporting jack, a nailing die, means for effecting relative approaching movement of the jack and die, an approximately counter-shaped member projecting from the die in register with the heel seat of a shoe upon the jack, and means for driving nails through said member to attach a counter supported upon the member to a 90 shoe upon the jack. 95

23. In a machine of the class described, the combination with means for supporting a lasted shoe, of a fastening inserting mechanism including a fastening guiding throat adapted to enter a molded counter located 100 in upright position on the bottom of the heel seat of the shoe and constructed and arranged to present a fastening guiding passage in the throat adapted to locate a fastening in the inturned flange of the counter 105 closely adjacent to its inner wall.

24. In a machine of the class described, the combination of means for supporting the heel seat portion of a shoe, means for holding a counter in upright position on the heel 110 seat of the shoe, means constructed and arranged to position the shoe and the counter relatively, and mechanism operating to attach the counter to the heel seat portion of the shoe. 115

25. In a machine of the class described, the combination of means for entering a shoe and supporting the heel end of the shoe sole, means for supporting a counter in upright position on the heel seat of the shoe, means 120 constructed and arranged to predetermine the relative longitudinal and transverse positions of the counter and the heel seat of the shoe, and mechanism operating to fasten the counter so positioned to the shoe. 125

26. In a machine of the class described, means for supporting a lasted shoe, an opposing member constructed and arranged to support a molded counter adjustably, means to locate the shoe in predetermined relation 130

to the counter, and means for fastening the counter in final position on the heel seat portion of the shoe.

27. In a machine of the class described, 5 the combination of mechanism organized to hold counters of differing characteristics in predetermined shape; means for supporting a lasted shoe in finally assembled relation to a counter, and means operating permanently 10 to attach the counter to the heel seat portion of a shoe.

28. In a machine of the class described, a

fastening inserting mechanism, means for holding a molded counter with its inturned flange within the field of operation of the 15 fastening inserting mechanism, means for supporting a lasted shoe in inverted position relatively to the counter, and means to predetermine the position of the heel seat of the lasted shoe relatively to the counter and to 20 the fastening inserting means.

In testimony whereof I have signed my name to this specification.

CHARLES E. CONNER.
